DESIGN FOR A HAMPER OR SIMILAR ARTICLE

Harold Gleitsman, New York, N. Y.

Application January 27, 1940, Serial No. 89,794

Term of patent 14 years

To all whom it may concern:

Be it known that I, Harold Gleitsman, a citizen of the United States, residing in New York, in the county of New York and State of New York, have invented a new, original, and ornamental Design for a Hamper or Similar Article, of which the following is a specification, reference being had to the accompanying drawing forming part hereof.

The figure is a perspective view of a hamper or similar article embodying my new design. The side which is not shown in the figure is identical with the side which is shown. The dominant features of the design reside in the mirror portions shown in solid lines.

I claim:

The ornamental design for a hamper or similar article, as shown and described.

HAROLD GLEITSMAN.
